UNITED STATES PATENT OFFICE.

REUBEN HALEY, OF BEAVER, PENNSYLVANIA, ASSIGNOR TO CONSOLIDATED LAMP AND GLASS COMPANY, OF CORAOPOLIS, PENNSYLVANIA, A CORPORATION OF WEST VIRGINIA.

DESIGN FOR A GLASS VASE.

Application filed June 29, 1928. Serial No. 27,315. Term of patent 7 years.

To all whom it may concern:

Be it known that I, REUBEN HALEY, a citizen of the United States, residing at Beaver, in the county of Beaver, and State of Pennsylvania, have invented a new, original, and ornamental Design for Glass Vases, of which the following is a specification, reference being had to the accompanying drawing, forming part thereof.

In the drawing—

Fig. 1 is a perspective view of the vase showing my new design;

Fig. 2 is a horizontal sectional view taken through the body of the vase; and

Fig. 3 is a vertical sectional view of a fragment of the wall of the vase.

I claim:

The ornamental design for a glass vase, as shown.

REUBEN HALEY.
